LUGGAGE HANDLE CLIP

George Lipschutz, Philadelphia, Pa.

Application October 8, 1943, Serial No. 505,439

1 Claim. (Cl. 190—58)

This invention relates generally to luggage hardware and more particularly to an improved construction of a clip for securing to the luggage that type of carrying handle which has the capacity, when not in use, of lying flat against the outer surface of the luggage, or of being arched away from said surface to provide a convenient and comfortable hand-hold for carrying the luggage.

Among the principal objects of the present invention is to provide a one-piece clip which is stamped out of sheet metal and includes as an integral part thereof an anchoring element which is adapted to project through a slot formed in the end of the strap handle whereby the anchored end of the handle is permitted a limited degree of movement relatively to the clip, a pair of such clips being employed for respectively anchoring the opposite ends of the handle in position.

A further and important object of the invention is to provide a clip of the character hereinbefore described in which the anchoring element is so formed as to be self-reinforced against the heaviest loads that may be carried by the handle, the clip being generally so designed as to resist any tendency for the strap handle to become disengaged from the luggage to which it is secured.

A still further object is to provide a luggage handle clip which is exceedingly simple in construction and design, inexpensive to manufacture, easily secured in position and exceedingly strong and durable in use.

Other objects and advantages will be apparent hereinafter, it being understood that the present invention consists substantially in the combination, construction, location and relative arrangement of parts, all as described in the following specification, as shown in the accompanying drawing and as finally pointed out in the appended claim.

In the accompanying drawing, which illustrates a preferred construction of the present invention:

Figure 1 is a plan view showing a handle secured in position by the clips constructed in accordance with and embodying the principles of the present invention;

Figure 2 is a side elevational view of the arrangement shown in Figure 1;

Figure 3 is a sectional view taken on the line 3—3 of Figure 1;

Figure 4 is a transverse sectional view taken on the line 4—4 of Figure 2;

Figure 5 is a perspective view showing a clip of the present invention;

Figure 6 is a top plan view of the clip;

Figure 7 is a sectional view taken on the line 7—7 of Figure 6; and

Figure 8 is a view similar to Figure 7 showing a somewhat modified form of the clip.

Referring now to the drawing and more particularly to Figures 5 to 7, it will be observed that 10 the clip of the present invention, designated generally by the reference numeral 10, is in the form of a one-piece sheet metal stamping of generally channel or U-shape having an upper flat part 11 and opposite depending side parts 12—12, 15 the free ends of which are outwardly turned to provide a pair of securing flanges 13—13. These latter flanges are respectively apertured, as at 14—14, to permit the insertion therethrough of suitable securing screws 15 (see Figures 1 and 2).

20 Struck out of the flat part 11 of the clip are a pair of more or less sharply pointed strap-anchoring elements 16—16, these latter being oppositely bent downwardly out of the plane of the part 11 and then passed into flatwise engagement with each other, as shown, to provide the clip with a centrally disposed depending anchor adapted to be projected freely through a slot suitably provided therefor adjacent one end of the strap handle which is to be secured to the 25 luggage. As clearly appears from Figures 5 to 7, the depending anchor, which is thus formed of a double thickness of the sheet metal out of which the clip is stamped, is so disposed that the opposed flat surfaces thereof are parallel the side parts 30 12—12 of the clip. In other words, the depending anchor is so disposed that the base 17 thereof by which it is integrally joined to the flat part 11 of the clip extends in a direction parallelizing the side parts 12—12 of the clip, that is, lengthwise of the strap handle, in consequence of which the anchorage 18 is afforded maximum 35 rigidity and strength against lengthwise pull of the strap thereagainst.

In use of the clip of the present invention, a 40 pair of them are employed, as shown in Figures 1 and 2, for anchoring in position the opposite ends of a strap handle 18. This handle is of conventional construction and is provided adjacent either end thereof with an elongated slot 19. 45 The clips 10—10 are respectively secured to the wall 20 of the luggage by the screws 15—15 in such manner that with the flat part 11 of each clip extending across the upper surface of the slotted end portion of the handle and the parallel side parts 12—12 of the clip embracing therebe-

50

tween said portion of the handle, the depending anchor projects downwardly into and through the slot 19 in the handle. Generally, the clips are so relatively secured in position that when the handle is disposed flatwise against the luggage wall, the depending anchorage elements 16-16 of the clips are spaced from the outer ends of the slots 19-19, thereby permitting a limited extent of inward movement of the opposite ends of the handle when the central portion thereof is flexed away from the luggage wall, as when it is used for carrying the luggage.

For all practical purposes, the struck-out parts 16-16 which jointly form the depending anchor, need be of a length only sufficient to present the free extremities thereof in close relation to the outer surface of the luggage to which the clips are secured, and in such case, these struck-out portions need not even be of the triangular or wedge shape as shown, but instead may be of any suitable shape having blunt free extremities. However, in certain cases, it may be desirable to secure the free extremity of the anchorage element to the luggage to provide a more rigid and secure anchor for the handle and in such case, the struck-out parts 16-16 are pointed as shown and formed of sufficient length (as shown in Fig-

ure 8) that their pointed extremities penetrate the wall of the luggage when the clips are secured in place, thereby providing rigid fastening of the anchorage element at top and bottom thereof. 5 Also, it will be understood, that by so increasing the length of the anchorage element and pointing its free extremity to effect its rigid securement to the luggage, it may be unnecessary to provide a pair of struck-out parts as shown for 10 each clip and instead only one such struck-out part, properly centered within the clip, may be employed without departing from the general principles of the present invention.

What is claimed as new and useful is:

15 A clip for a luggage handle of the type having elongated slots in the opposite end portions thereof comprising a U-shaped member adapted to be secured to the luggage in embracing relation with respect to each slotted portion of the handle, said 20 member including a flat part extending across and overlying the slotted portion of the handle and said flat part including a pair of struck-out elements oppositely bent out of the plane thereof and pressed into flatwise engagement with each 25 other to provide a depending anchorage adapted for projection into the handle slot.

GEORGE LIPSCHUTZ.
